United States Patent Office

Des. 186,327
Patented Oct. 13, 1959

186,327

GOBLET OR THE LIKE

Robert S. Holt, Greensburg, Pa., assignor to Bryce Brothers Company, Mount Pleasant, Pa., a corporation of Pennsylvania

Application June 17, 1959, Serial No. 56,404

Term of patent 14 years

(Cl. D36—8)

Fig. 3

I claim:

The ornamental design for a goblet or the like, as shown.
